Primary Examiner — Brett Miller*Assistant Examiner* — Jessica M Gebhart(74) Attorney, Agent, or Firm — Andrew C. Cheng(57) CLAIM

The ornamental design for a laptop briefcase as shown and described.

DESCRIPTION

FIG. 1 is a top, front, right perspective view of a laptop briefcase of my new design;

FIG. 2 is a bottom, rear, left side perspective view thereof;

FIG. 3 is a front view thereof;

FIG. 4 is a rear view thereof;

FIG. 5 is a left view thereof;

FIG. 6 is a right view thereof;

FIG. 7 is a top view thereof; and,

FIG. 8 is a bottom view thereof.

The broken lines in the figures depict portions of the laptop briefcase that form no part of the claimed design. The zipper stitching shown in the figures also forms no part of the claimed design.

1 Claim, 8 Drawing Sheets(56)
